UNITED STATES PATENT OFFICE.

ALEXANDER F. J. JOHNSON, (NOW BY JUDICIAL CHANGE OF NAME ALEXANDER F. JENKINS,) OF BALTIMORE, MARYLAND, ASSIGNOR TO ALEXANDER MILBURN COMPANY, OF BALTIMORE, MARYLAND, A CORPORATION OF MARYLAND.

ACETYLENE GENERATOR AND TORCH.

1,011,436.

Specification of Letters Patent.

Patented Dec. 12, 1911.

Application filed November 29, 1907. Serial No. 404,307.

To all whom it may concern:

Be it known that I, ALEXANDER F. J. JOHNSON, now ALEXANDER F. JENKINS, a subject of the King of Great Britain, residing at Baltimore, in the State of Maryland, have invented new and useful Improvements in Acetylene Generators and Torches, of which the following is a specification.

10 This invention relates to acetylene generators and more particularly to combined generators and torches of the portable type intended for use by contractors, engineering concerns and the like to carry on construction or other work by night and in dark places.

15 The invention has for one of its objects to improve and simplify the construction and operation of apparatus of this character so as to be comparatively easy and inexpensive to manufacture, designed to stand rough usage in the hands of unskilled persons, and readily manipulated.

20 A further object of the invention is to provide a generator in which the generating element has combined therewith a washer through which the gas is conducted for purifying before it passes to the point of consumption, the said element and washer 25 constituting a unitary structure or unit, which can be sold to the trade with or without an outer water containing casing or tank, as no special kind of tank will be required, and in fact an ordinary barrel may 30 be employed to receive the unit and the water in which the latter is submerged.

35 Another object of the invention is to arrange the washer on the generator and to provide a simple means for conducting the 40 gas from the generator to and through the washer, and to the torch or burner, which may be mounted directly on the generator by means of a standard, or connected therewith by a hose or the like for supplying 45 one or more burners located at a distance from the generator.

With these, and other objects in view, the 50 invention comprises the various novel features of construction and arrangement of parts which will be more fully described hereinafter and set forth with particularity in the claims appended hereto.

In the accompanying drawings, which illustrate certain embodiments of the inven-

tion, Figure 1 is a central vertical section of the complete apparatus, with portions in elevation. Figs. 2, 3 and 4 views of various modifications of the invention. Fig. 5 is a detail view of the spring lock for holding the inner and outer cylinders of the generator together. Fig. 6 is a detail sectional view on line 6—6, Fig. 1.

Similar reference characters are employed to designate corresponding parts in the several views.

Referring to the drawings, A designates the tank or casing for the generator, and it may be of any preferred construction, and a barrel or other available receptacle may be employed. The tank is adapted to hold water and submerged therein is the generator B, which is readily removable for recharging with carbid or for other purposes.

The generator comprises an outer cylinder 1 which is open at its bottom and closed at its top, and housed therein is an inner cylinder 2 which is open at its top and closed at its bottom. The inner cylinder is inserted and removed through the open bottom of the outer cylinder, and the two are locked together so that they can be removed from or placed in the tank A at one time. The locking device employed for this purpose consists of a stiff leaf spring 3 secured to the outside of the cylindrical wall of the part 2, and the lower end of the spring is adapted to enter a notch 4 in the top edge of an internal band 5 secured to the outer cylinder at the bottom thereof. In assembling the outer over the inner cylinder, the spring will be pressed inwardly by the band 5 coming into contact therewith and as the band passes beyond the lower end of the spring, the latter will fly outwardly and engage over the top of the band. If the spring does not enter the notch 4 at once, the outer cylinder is turned back or forth until the spring snaps into the notch, and when this occurs the spring will be opposite an opening 6 in the outer cylinder, which opening permits of the insertion of a finger for releasing the spring when it is desired to disconnect the cylinders.

The inner cylinder 2 is of somewhat less diameter than the outer so that water can enter between the two cylinders and water feeds into the inner one through the inlet openings 7 which are provided in the wall

of the cylinder 2 at different heights, so that when the demand for water is light it will pass through only the lowermost opening, and as the demand increases the water will 5 pass also through one or more of the other openings. The water is directed downwardly to the bottom of the inner cylinder by a shield 8 suitably secured to the latter, and the water gradually feeds upwardly 10 through the carbide holders C during the operation of the generator. When the generator is placed in the tank, the unoccupied space in the former is filled with air which prevents water from reaching the carbide 15 so that no gas will be generated. As soon as the burner valve is opened the air escapes and water then flows to the carbide. A gas pressure will now be produced which has the effect of holding back the flow of water 20 to the carbide and should the valve be closed the back pressure of the gas will entirely stop the water feed. But as long as gas is consumed by the burner water will feed in just sufficient quantity to generate the desired gas. The holders C are in the form 25 of trays fitted in and resting one on another within the cylinder 2, and if desired the trays may be divided into carbide holding compartments by partitions 9, the water 30 entering the compartments to act on the carbide through openings 10 arranged at different levels, so that water will enter the compartments of the several trays successively and when the carbide is consumed the water 35 will have reached the level shown. The generated gas passes upwardly and flows out from the generator by way of an outlet pipe 11 which has its lower end secured to the top of the outer cylinder and communicating 40 with the latter through an opening in the said top.

The gas, before being conducted away to the point of consumption, is passed through a washer to be purified. For this 45 purpose a washer D is arranged on the generator and forms therewith a unitary structure. As shown in Fig. 1, it consists of a frusto-conical receptacle 12 resting on and secured to the top of the generator, and the 50 bottom of the receptacle is formed by the top of the cylinder 1. In the washer and surrounding the outlet pipe 11 is another pipe 13 which is closed at its upper end so as to receive the gas from the inner pipe and 55 conduct it downwardly to the apertures 14, which latter admit the gas to the washer. The gas passes through the water 15 to be cleansed and then rises to the top of the washer from which it is conducted away to 60 be consumed. Surrounding the upper end of the pipe 13 is a tube that communicates with and rests on the washer and carried by the upper end of this tube is a burner standard E, having a swinging section 16 which 65 is equipped with a burner 17 of any ap-

proved form, the supply of gas to the burner being controlled by the valve 18. It will thus be seen that the generator, washer and burner constitute a self-contained structure which is entirely separate from the tank and no piping or connectings between the generator and washer and the tank are required. The washer is filled by means of an opening 19 which is normally closed by a plug 20. The washer is emptied through 75 this opening and also the level of the water determined.

When the generator is furnished with a tank, a locking device is employed for holding the generator in place so that it will not 80 be inadvertently removed by a person attempting to transport the apparatus from place to place by taking hold of the burner standard. This device comprises in the present instance a leaf-spring 25 which has its upper end secured to the tank and its lower end disposed to engage over the top 85 of the generator.

In order to determine the amount of unconsumed carbide in the generator at any 90 time, a level indicator F is mounted in the tank. When the generator is fully charged and before any of the carbide is acted on by the water the level of the latter will be even with the upper division of the indicator or 95 scale. As the carbide is consumed the water level changes and by suitable divisions on the scale the fraction of unconsumed carbide can be quickly ascertained.

One of the important advantages resulting 100 from locating the washer on the generator, resides in the fact that the weight of the water in the washer tends to hold the generator submerged, as for instance, when the generator is used in an ordinary barrel or the like without the lock 25. It may be remarked in this connection that the generation of gas in the generator gives buoyancy 105 to the latter so that it tends to rise out of the water, and by weighting the generator 110 by the washer this tendency is overcome.

In the modified form shown in Fig. 2, the washer D is of cylindrical shape and the gas is conducted from the generator B to the washer by the siphon-shaped pipe 21 which 115 has its outlet end submerged in the water in the washer. In this instance the washed gas is conducted away from the washer by a hose 22 which may supply one or more burners located remotely to the generator.

In Fig. 3, the washer D is shown set partially into the generator and the inverted U-shaped pipe 23 extends through the side of the washer, while in the form shown in Fig. 4, the pipe 24 leads into the top of the 125 washer and conducts gas to the latter from the generator.

From the foregoing description, taken in connection with the accompanying drawing 130 the advantages of the construction and

method of operation, will be readily understood by those skilled in the art to which the invention appertains, and while I have described the principle of operation, together with the apparatus which I now consider to be the best embodiment thereof, I desire to have it understood that the apparatus shown is merely illustrative, and that the invention can be carried out in other ways, within the scope of the claims.

What I claim as new and desire to secure by Letters Patent of the United States, is:

1. A portable acetylene generator consisting of separable inner and outer drums, the outer drum being open at its bottom and assembled over the top of the inner drum, the inner drum being open at its top, means for holding carbid in the inner drum, a gas outlet pipe having its lower end anchored on the top of the outer drum and open at both ends to permit gas to discharge therethrough from the outer drum, a pipe of larger diameter surrounding the first-mentioned pipe and closed in its top, a washer disposed on the top of the outer drum and surrounding the lower end of the said pipe, a gas discharging means rising from the top of the washer and forming a handle rigidly connected with the generator, a burner connected with the said discharging means, in combination with a water-containing tank of such depth that the generator is submerged therein with the said discharging means extending out of the tank to be gripped in inserting or removing the generator.

2. In an apparatus of the class described, the combination of a generator comprising an inner drum open at its top and closed at its bottom, an outer drum closed at its top and open at its bottom for assembling over the top of the inner drum and being of larger diameter than the latter to form an annular water space in which water can rise to enter the inner drum, and means for holding carbid in the inner drum, a locking device for holding the drums in assembled relation during insertion and removal of the generator, and means carried entirely by the generator for conducting gas away from the latter; with a water-containing tank in which the generator is submerged and removably held in place, the generator being so disposed that the bottom of the annular water space thereof is in free communication with the space surrounding the generator to permit water to freely enter the generator from the tank.

3. In an apparatus of the class described, the combination of a tank open at the top, with a generator separate from and removably submerged in the tank and free at all times to turn about its axis in the tank, an outlet pipe fixed on and movable with the generator and forming a handle for the gen-

erator in placing and removing the latter into and from the tank, and a burner-carrying arm on the pipe arranged to swing on a horizontal axis and to move with the generator when the latter is turned for directing the flame in any direction.

4. In an apparatus of the class described, the combination of a tank, with a generator removably mounted therein, said generator comprising an inner drum, a spring secured to the outside thereof with its lower end free and standing away from the drum, an outer drum surrounding the inner drum, an internal reinforcing band secured to and extending entirely around the outer drum and arranged to be engaged by the lower end of the spring to lock the inner and outer drums together, and means for holding carbid in the inner drum.

5. In an apparatus of the class described, the combination of a generator, a washer mounted on the top thereof and provided with a filling and emptying opening, said opening serving to determine the level of the water in the washer, a stopper for the opening, and a burner carrying conduit connected with the washer, with a tank containing the said generator and out of which the said conduit rises to form a handle whereby the generator can be inserted or removed, and a locking device for normally locking the generator in the tank.

6. In an apparatus of the class described, the combination of a generator composed of an outer closed top drum and an open top carbid-holding inner drum, a washer on the top of and fixed to the outer drum, means for conducting gas from the top of the generator to the bottom of the washer, said washer and generator being permanently connected to form a unitary structure, an outlet conduit connected with the top of the washer and forming a burner support, with a tank in which the generator is submerged and out of which the outlet conduit rises, said generator being capable of turning in the tank for throwing the flame in a horizontal plane.

7. In an apparatus of the class described, the combination of a tank, a generator submerged therein, and a water level indicator attached to and arranged wholly within the tank to be submerged in the water therein for determining the amount of carbid in the generator at any time.

8. A portable generator and torch comprising a water-containing tank having an opening at the top; and a gas generating, washing and burning unit entirely separate from the tank and insertible into and removable from the latter through the open top, said unit consisting of the following; the first drum having an open bottom resting on the bottom of the tank and of such height as to be submerged in the latter, a closed bottom and open top carbid-holding drum remov-

ably mounted in the outer drum, a washer above the first drum and having its bottom formed by the top thereof, means for conducting gas from the top of the first drum to the washer, a discharge means leading from the washer and forming a handle rising out of the tank for the said unit, and a burner connected with the discharge means.

9. A portable generator and torch including a water-containing tank open at the top, a generator normally within and entirely separate from the tank and removable from the top thereof, an upwardly extending gas-conducting pipe on the top of the

generator serving as a handle to be grasped 15 for the removal and insertion of the generator, and a leaf spring arranged in the tank with its upper end fixed and its lower end free to yield laterally during the insertion of the generator and to snap over and engage 20 the latter for preventing lifting thereof.

In testimony whereof I affix my signature in presence of two witnesses.

ALEXANDER F. J. JOHNSON.
